HEEL OF SHOES WORN BY MEN, WOMEN,
AND CHILDREN, OR BY ANIMALSFrank Greenberg, New York, N. Y., assignor of
one-half to Harry Malter, New York, N. Y.

Application June 30, 1943, Serial No. 492,792

4 Claims. (Cl. 36—36)

This invention relates to heels for shoes, and more particularly to heels adapted to be attached, detached or interchanged by the shoe owner without requiring the services of a shoe repair man or the employment of special tools.

At the present time, shoe heels are permanently secured to the fixed heel portion of a shoe, by means of nails or adhesives or a combination of both. Most shoe wearers very rapidly wear heels down angularly so that while the major portion of the heel is capable of considerably more use, the heels are quickly discarded to avoid a "run down" appearance. This not only greatly increases the upkeep of a pair of shoes, but each heel replacement requires the services of a shoe repair man who is not always available.

The present invention contemplates the provision of a detachable heel construction by means of which a heel can be instantly attached or detached without requiring any skill or any more tools than an ordinary screw-driver. Through such instantaneous attachment of the heels it will be obvious that when a pair of heels becomes worn down toward one side, the heels can be given increased life by being shifted from one shoe to the other. Moreover, when a new pair of heels is to be fitted, such fitting can be done by the shoe owner, or several pairs of heels can be sold with each pair of shoes so that the shoe buyer will be supplied with sufficient heels to last for the life of the shoes. Many other advantages will be apparent to those skilled in the art, as the description of the invention proceeds.

More particularly, the invention contemplates the provision of a detachable heel construction in which the fixed heel part of a shoe will be provided with a plurality of embedded and concealed fastener elements and with openings extending through said heel part permitting access to said fastener elements, and the detachable heel part will be provided with stud portions entrant through said openings to detachably, but securely, engage the fastener elements to attach the detachable heel part in place.

In the accompanying drawing, wherein an illustrative embodiment of the invention is shown, Fig. 1 is a view of the under face of a detachable heel construction, made in accordance with the invention; Fig. 2 is a view of the bottom face of the fixed heel part, with a portion thereof being broken away to disclose one of the fastener elements; Fig. 3 is a top plan view of the detachable heel part, showing the stud

fastener elements arising therefrom; Fig. 4 is a sectional view on the line 4—4 of Fig. 2, looking in the direction of the arrows; and Fig. 5 is a sectional view through a part of the detachable heel, showing the construction of one of the stud fasteners.

In the drawing, the heel construction is shown as applied to a shoe of conventional form, a portion thereof being indicated at 1, and to which is secured a fixed heel part 2 made in the usual manner and thus composed of a number of layers or plies 5 which may be of leather or of any other suitable material commonly used in shoe construction.

The detachable heel portion is shown at 3, and the same may be made of rubber, leather, composition, or any other suitable material, and it is adapted to be securely, yet firmly attached to the under face of the fixed heel part 2 by the interlock of suitable fastening elements to be described.

Provided between the layers of the fixed heel part 2, is a plurality of spaced recesses or pockets 6, and in each of these pockets or recesses is located a fastening element, consisting of a pair of spaced posts or pins 7, connected by a substantially S-shaped spring wire 8. Leading into each of the recesses or pockets 6 is an opening or hole 10, which extends through the bottom layer or ply of the fixed heel portion, and the central part 9 of the resilient wire 8 extends across said opening 10 and is therefore accessible for engagement by one of the studs 12 carried by the removable heel portion 3.

The heel portion 3 is provided with a plurality of spaced studs 12 corresponding in number to the spring wires 8. Each of the studs 12 has a slotted head 13 and each stud is manually rotative in a sleeve 11 anchored or embedded in the heel portion 3, or otherwise fixedly secured therein. It will be observed that the studs 12 and the anchorages 11 thereof are located toward the upper face of the heel portion 3 and that a considerable part of the length of each of the studs arises from said face so that when the detachable heel part 3 is placed with said face disposed against the lower surface of the fixed heel part 2, the studs will enter through the openings 10 for interlocking engagement with the spring wires 8 to securely attach the detachable heel portion 3 to the fixed heel part 2.

Each of the studs 12 is transversely slotted at its outer end, as indicated at 15, and said end is so shaped as to provide two oppositely-disposed hook members 16 and 17 which engage over the

wire 8 by manual rotation of the stud. To permit such manual rotation, the detachable heel portion 3 is provided with an opening 14 in axial alignment with each of the studs 12 whereby a screw driver or other suitable tool can have access to the slotted head 13 of the stud to turn the same.

From the foregoing, the operation of the improved heel construction will be readily understood. To attach the part 3 of the heel to the fixed portion 2, the part 3 is held against the bottom of the part 2 so that the studs 12 will pass through the openings 10 and the central portions 9 of the wires 8 will enter the transverse slots 15 in the ends of the studs 12. By means of a screw driver inserted in each opening 14, each stud is rotated slightly to cause the oppositely-disposed hooked ends 16 and 17 to ride over the wire so that the wire will be held under the hooks and located in the transverse opening 18 in the stud. The tension of the wire holds the studs against rotative movement and also holds the heel part 3 firmly against the bottom of the fixed heel part and the fastener parts held in interlocked position indefinitely. To detach the heel part 3, the studs 12 are rotated until the wires are aligned with the slots 15, whereupon the heel portion 3 can be lifted away.

The advantages of the construction described will be readily appreciated. When a heel becomes worn or run down, and particularly toward one side, it may be instantly detached and exchanged with the heel on the other shoe so that as a result, each heel will have a greatly extended useful life. Since the heels can be attached and detached by the wearer, and without requiring the services or tools of the repair man, shoe manufacturers can supply several sets of heels with each pair of shoes and the replacement of worn heels becomes the work of but a moment.

While I have described the structure for use in connection with the attachment of heels to shoes for human wear, shoes of animals may be attached in the same manner. Additionally, soles as well as heel parts may also be applied. These and other embodiments of the invention are contemplated by the claims appended hereto.

What I claim is:

1. In a detachable heel construction, a fixed heel part, a removable heel part having rotatable studs provided with heads accessible from the outer face of the removable heel part to permit of manual rotation of said studs, the fixed heel part having recesses opening at the face of said part, spaced pins adjacent to said recesses, a flexible

wire extending across the recess and connecting the spaced pins, and reversely extending arcuate slots provided in the studs for interlocking engagement with the wires when the studs are entered into the recesses and turned rotatively within the same.

2. In a detachable heel construction, a fixed heel portion composed of a plurality of layers having several spaced pockets formed between them, a pair of spaced pins located in each pocket, a spring wire extending across the pocket and attached at its ends to the pins, said fixed heel portion having an opening extending from each pocket and through its outer layer, a removable heel part for fitment over the outer face of the fixed heel part, said removable heel part having spaced rotatable studs for entry through said openings, each of the studs having a transverse slot and oppositely extending hooked ends whereby a wire will enter said slot when the stud enters one of the openings and the hooked parts of the stud will be projected over the wire and caused to be locked thereover when the stud is manually rotated.

3. A detachable heel construction comprising, a fixed heel portion provided with a plurality of spaced recesses, a pair of spaced pins located in said recess, a resilient wire connecting said pin, the heel part having a hole leading from said recess through the outer face of said heel part, said wire extending crosswise of the hole, a detachable heel part having a plurality of rotatable studs secured in it and projecting from one of its faces, each of said studs being transversely slotted and formed with reversely hooked ends, each stud being entrant through one of the holes to bring its slot in engagement with the wire extending across the hole, whereby said stud, when rotated, will have its hooked ends engaged over said wire, and the detachable heel part secured over the fixed heel part by such interengagement of the studs and wires.

4. In a detachable heel construction, a fixed heel part on a shoe, a removable heel part for attachment thereover, one of the heel parts having several rotatable studs provided with accessible heads to permit manual rotation of said studs, the second heel part having recesses opening at one of its faces, a flexible wire mounted to extend across each recess, the studs each having a slot and a hook portion on each side of the slot whereby the stud, upon entering a recess, will cause the wire to enter the slot and by manual rotation of the stud the hook portions thereof will become engaged over the wire.

FRANK GREENBERG.
